UNITED STATES PATENT OFFICE

WILLIAM G. ESMOND, OF STRATFORD, CONNECTICUT, ASSIGNOR TO EDGAR AMES, OF NEW YORK, N. Y.

DECK STRUCTURE FOR BARGES

Application filed September 4, 1929. Serial No. 390,404.

This invention relates to barges, boats and the like somewhat of the type shown by the Ellis Patent No. 1,596,723, and relates more particularly to loading decks therefor though it is noted that the invention is not limited to barges nor in some respects even to boats.

One object of the invention is to provide a boat or structure of this kind having a cushioned loading deck.

Another object of the invention is to provide in a structure of this kind an improved log rail for retaining the load on the deck.

Another object of the invention is to provide an improved, renewable, replaceable armored log rail, and an improved raised deck associated with the loading deck.

Other objects of the invention are to improve generally the simplicity and efficiency of such structures and to provide a structure of this kind which is durable and watertight and well drained in use, and economical to construct.

Still other objects of the invention will appear as the description proceeds; and while herein details of the invention are described and claimed and the claims mention barges, the invention is not limited to these, since many and various changes may be made and the structure may be applied to boats and platforms without departing from the scope of the invention as claimed in the broader claims. Therefore the claims are not to be construed as limited to barges or boats.

The inventive features for the accomplishment of these and other objects are shown herein in connection with an improved barge which, briefly stated, includes a frame having transverse deck beams supporting a plate secured to the sides of the barge and over the ends of the beams. Transverse angle pieces secured on said beams remote from the ends of the barge, and longitudinal angle pieces secured on the outer margin of said plate engage the ends and sides of a wooden loading deck carried on said beams. Additional angle members are secured to said transverse pieces and engage over the ends of the deck.

Wooden log rails on the deck margins engage said members and longitudinal pieces; and a gunwale plate is secured on the outer upper part of the barge side, said longitudinal piece and rail, and forms a cover portion over the rail; said gunwale plate and log rail having scuppers passing therethrough. Deck plates over the ends of the barge resting on said cover portion and said member may carry deck house machinery or the like.

In the accompanying drawings showing, by way of example, one of many possible embodiments of the invention.

Fig. 1 is a fragmental side elevation of the barge;

Fig. 2 is a fragmental transverse vertical sectional view, partly in elevation, of the barge, the section being taken substantially on the line of 2-2 Fig. 1, looking in the direction of the arrows of said line;

Fig. 3 is a fragmental transverse vertical sectional view, drawn to a larger scale, the section being taken substantially on the same line 2-2 of Fig. 1, looking in the direction of the arrows of said line;

Fig. 4 is a fragmental side elevation showing a portion of the side of the barge;

Fig. 5 is a fragmental side elevation showing the piece of one of the notched truss members; and

Fig. 6 is a fragmental perspective view showing parts of the log rail, the deck and said transverse pieces.

My improved loading deck is shown in combination with a barge preferably of steel except where other material is specified though it is noted that the invention is not in all respects limited to a metal construction.

While the invention is not limited to any particular form of frame, the parts are shown mounted on a frame comprising transverse trusses 10 having transverse upper and lower frame members 11 and 12, side frame members 13, corner plates 14 joining the ends of the members, and uprights and lattice members 15 and 16 respectively intermediately connecting the upper and lower frame members 11 and 12.

Longitudinal members 18 secured to the

uprights and the inner edge faces of said upper and lower members and braces 19 serve to strengthen the frame longitudinally.

The side and bottom plates of the barge 5 comprise channel shapes 20, 21 and 22 (Figs. 1 and 3) extending from one end to the other of the bottom and sides of the barge, and riveted to the members 12 and 13, and having inwardly turned flanges 23, 24 disposed in notches 25 (Figs. 1, 3 and 6) in the members 12, 13, and engaging the flanges of adjacent shapes and riveted thereto by means of rivets 26 (Fig. 3).

Curved shaped bilge plates 28 overlap and 15 are riveted to adjacent marginal shapes 21 and 22 of the sides and bottom, and are strengthened by curved transverse angle pieces 29.

The upper members 11 form deck beams 20 carrying plates 30 riveted to the upper flange 23 of the uppermost side channel shape and lying on and riveted to the ends of the deck beams.

A wooden loading deck 32 of longitudinal 25 strips of cushioning wood flooring is laid on said deck beams and plates 30 with the ends of the strips resting on a lower flange 34 and abutting an upstanding flange 33, Fig. 5, of a transverse angle piece 35 extending across 30 the barge near each end thereof, the flange 33 being riveted flat to a vertical transverse or cross plate 36 intermediately riveted to the uprights 16 and having its lower edge riveted to an angle piece 37 riveted to the 35 members 18.

A longitudinal angle piece 38 (Fig. 3) mounted on the outer edges of said plate 30 comprises an upturned flange 39 engaged by the outer deck strip 40, and a flange 41 flat 40 on said plate 30 and secured thereto by means of rivets 42 extending through said plate and the adjacent flange 23 of the adjacent channel shape.

A load retaining and cushioning wooden log 45 rail 50 (Figs. 1 and 3) on the outer flooring strips abuts said cross plate 36 and is rabbed to receive said upturned flange 39, Fig. 3. This rail is extended a considerable distance above the level of the deck and is chamfered at its upper outer longitudinal corner 51.

Caulking 52, 53 (Fig. 3) and 54 (Fig. 5) is forced between the lower inner corner of the log rail and said deck, between the outermost deck strip 40 and said upturned flange 39, and between the flange 33 and the ends of the deck strips, to prevent the entrance of water below the deck. Said vertical cross plates 36, certain angle pieces and said log 60 rail 50 serve to form a load receiving well.

A combined gunwale, collision and rubbing plate or armor 55 (Figs. 3 and 5) secured on and riveted to the outer face of the upper channel shapes 23, 24 and said upturned flange 39 and the outer face of the log rail

is curved over the chamfered portion 51 and forms a cover portion 56 covering the top face of the log rail. Large screws 57 passed through said cover portion into the log rail serve for holding the log rail in place; and permit the removal and replacement of the log rail by removal of the screws.

A rubbing plate 58 (Figs. 1 and 2) may be secured along the sides of the barge some distance below the gunwale plate.

The log rails, transverse plates 36 and certain angle pieces cooperate to form a well; the log rails and gunwale plates having scuppers 60 passing therethrough at the level of the deck flooring to drain the well.

The end deck beams 62 (Fig. 1) are raised above the level of the beams 11; and at each end a deck house plate 63 (Figs. 1 and 5) is secured entirely over the rake 64 of the barge and rests on the beams 62, said cover portion 56 of the plate 55 and an upper angle piece 65, riveted to the upper edge of the plate 36 and is adapted to receive a deck house 67, machinery and the like.

While the claims herein mention barges, 90 it is understood that they are to be construed broadly enough to cover any floating or fixed structures having corresponding parts.

The deck being of wood or other cushioning material provides a broad cushioning 95 floor adapted to receive, without shock to the frame, any load such as stone, ores, hardware and the like which may be lowered or dropped thereon.

The log rail and the transverse plates 36 100 and angle pieces 65 forming the well, serve to prevent the load from rolling or sliding from the deck.

The gunwale plate is slightly yieldable or springy; and the log rail being of wood or other cushioning material withstands shocks from cargo or the like which may strike against the gunwale plate, but is at the same time protected, from wear and cutting, by the gunwale plate. Removal of the screws 105 57 permit the log rail to be replaced from time to time when its fibers become rotted or too much shattered by the shocks.

I claim as my invention,

1. In a barge, deck beams; a longitudinal 115 plate secured over the ends of the beams; a longitudinal angle piece secured on the outer margin of said plate; a loading deck on said beams and engaging said angle piece; a log rail on the deck also engaging said angle 120 piece; and a gunwale plate attached to the side of the barge and extending inwardly over the longitudinal plate, angle piece and log rail and secured to the top of the latter.

2. In a barge, deck beams; a longitudinal 125 plate secured over the ends of the beams; a longitudinal angle piece secured on the outer margin of said plate; a wooden loading deck on said beams and engaging said angle piece; a log rail on the deck also engaging said 130

angle piece; and a gunwale plate secured on the outer upper part of the barge side, to said longitudinal angle piece and to said rail, and formed with a cover portion over the rail, to which is secured.

5. 3. In a barge, a deck; a log rail on the edge of the deck; and a gunwale plate secured on the outer upper part of the barge side, and formed with a cover portion over the rail and secured thereto; the log rail being removable without disturbing the operative position of said gunwale plate.

10. 4. In a barge, a frame, vertical cross plates mounted on said frame; angle pieces mounted on said plates, a loading deck on said frame and engaging said pieces, log rails on the deck margin also engaging said pieces, said rails having scuppers passing therethrough and gunwale plates secured to the side of said barge and bent inwardly to rest on the tops of said log rails and which are removably secured thereto.

15. 5. In a barge, a frame comprising deck beams; sides secured to said frame and beams; a plate secured to said sides and over the ends of the beams; a vertical cross plate secured to said frame; a transverse piece secured on said cross plate; a longitudinal piece on the outer margin of said first mentioned plate; a loading deck on said beams and engaging said pieces; a log rail on the deck margin engaging said pieces; a gunwale forming a cover portion for the top and outer face of the rail; and a rubbing plate secured along the sides of the barge some distance below the gunwale plate; said log rails and cross plate cooperating to form a well; the log rails and gunwale plates having scuppers passing therethrough at the level of the deck flooring to drain the well.

20. 6. In a barge, a frame including deck beams; sides secured to said frame and beams; a plate secured over the ends of the beams; a vertical cross plate secured on said frame; a transverse piece mounted on the cross plate; a longitudinal piece secured on the outer margin of said cross plate; a wooden loading deck of longitudinal strips on said beams and engaging said pieces; a load retaining and cushioning wooden log rail on the outer flooring strips and abutting said transverse cross plate and rabbeted to receive said longitudinal piece and extended a considerable distance above the

25. level of the deck floor and chamfered at its upper outer longitudinal corner; caulking forced between the lower inner corner of the log and said deck, between said deck and transverse piece, and between said outmost strip and said longitudinal piece to prevent the entrance of water; said cross plate and said log rail serving to form a load receiving well; a gunwale plate secured on and riveted to the outer face of the upper margin of the

30. barge side and said longitudinal piece and

the outer face of the log rail, and curved over the chamfered portion, and forming a cover portion secured on and covering the top face of the log rail; and large screws passed through said cover portion into the log rail 70 for holding the cover portion of the gunwale plate in place; the rail and gunwale plate having scuppers passing therethrough at the deck level.

7. In a barge, the combination of transverse trusses comprising transverse upper frame members forming deck beams, lower frame members, and side frame members, corner plates joining the ends of the members, and uprights and lattice members intermediately connecting the upper and lower frame members; longitudinal members secured to the uprights and the inner edge faces of said upper and lower members; the outer edge of the lower and side members 85 being provided with notches; side and bottom plates comprising channel shapes extending from one end to the other of the bottom and sides of the barge, and riveted to the notched members and having inwardly 90 turned flanges disposed in said notches and riveted to and engaging the flanges of adjacent shapes; curved shape bilge plates overlapping and riveted to adjacent marginal channel shapes of the bottom and sides; 95 transverse strengthening pieces secured to said bilge plates; and a deck laid on said deck beams.

8. In a barge, a frame comprising loading deck beams; sides secured to said frame and beams and having an inturned upper flange; a horizontal plate riveted to the upper flange and lying on and riveted to the ends of the deck beams; vertical cross plates mounted on said frame; transverse angle pieces extending across the barge near the respective ends of the barge and each having one flange upstanding and riveted flat to the cross plate; a longitudinal angle piece mounted on the outer edge of said horizontal plate and comprising an upturned flange, and a flange flat lying on said plate and secured thereto by means of rivets extending through said plate and said inturned flange; and a loading deck 110 of longitudinal strips of cushioning wood 115 flooring laid on said beams and plate with their ends abutting said upstanding flange, the outermost strip engaging said upturned flange.

9. In a barge, a frame comprising transverse deck beams and transverse raised end beams; a wooden loading deck on said deck beams; vertical transverse plates riveted to the end deck beams; and a deck plate on said transverse plates and raised beams. 120 125

10. In a barge, the combination of a frame having transverse deck beams and raised end beams; sides secured to said frame and beams; horizontal plates secured to said sides and over the ends of the deck beams; 130

- vertical cross plates; transverse angle pieces secured to the vertical plates; longitudinal angle pieces secured on the outer margin of said horizontal plates; a wooden loading deck on said beams and extending to and engaging the angle pieces; an angle member secured to the upper edge of said cross-plate and having an upper horizontal flange; a log rail on the deck margin engaging said pieces; a gunwale plate secured on the outer upper part of the barge side, said longitudinal piece and rail, and forming a cover portion over the rail extended to and mounted on the ends of the raised beams; said gunwale plate and log having scuppers passing therethrough; and a deck house plate mounted on said cover portion, said horizontal flange and said raised beams.
11. In a barge construction a frame consisting of transverse and longitudinal members and channeled side plates; longitudinal plates secured to the upper side flange of the uppermost side plates; transverse vertical plates; angle pieces riveted along the bottom edge of the transverse plates by which they may be secured to longitudinal members of the barge frame; angle pieces riveted at near the longitudinal center of the transverse plates and extending from side to side of the barge; a wooden deck resting on said last named angle pieces and on said longitudinal plates; other angle pieces riveted near the upper edges of said transverse plates; deck house plates riveted to these last named angle pieces, gunwale plates extending up the sides and bent over the deck of said barge; and log rails secured between the said deck and the bent over portions of said gunwale plates.
12. In a barge construction, a frame including vertical and horizontal members, and channeled side plates; ledge plates secured to the uppermost side plates, a wooden deck having one or more of its side slats resting on said ledge plates, log rails on the edges of said deck, gunwale plates secured to the side plates and having each a horizontal flat inturned guard portion overlying and secured to said log rails, vertical transverse plates having lower, middle and upper angle pieces secured thereto and extending across the barge frame; the lower angle pieces being secured to longitudinal members of the frame, the middle angle pieces having a ledge on which the ends of the deck slats rest and the upper angle pieces being secured to the deck house plates at the ends of the barge structure.
13. In a barge including in combination, longitudinal, and vertical frame members and channelled side plates, ledge plates; a wooden deck; log rails on the edges thereof; gunwale plates secured to the side plates and extending over to enclose the outer and top sides of the log rails to protect them; fastening devices passing through the overlying portions of the gunwale plates and into said log rails to hold them in place; deck house plates; vertical cross plates extending upward to the level of the gunwale plates, angle pieces riveted to the lower middle and upper portions of said transverse plates; the lower pieces being secured to the barge frame, the middle pieces supporting the ends of the wooden deck and the upper pieces supporting the said deck house plates as shown.
14. In a barge construction, the combination with interconnected channeled side plates, a wooden deck extending from side to side of said barge, plates and angle plates secured to the upper flange of the uppermost channeled side plate, the wooden working deck having rabbeted edges to receive said plates, a log rail disposed over the edges of said working deck and having a groove to receive one of said plates, a gunwale secured to the side plates and extending inwardly onto the top of said log rail, means for removably securing the log rail under the gunwale; and vertical transverse plates extending across the barge near its ends to collectively form with the opposite log rails, the side walls of a load receiving well.
15. In a barge construction, a frame, a wooden deck, deck house plates and vertical cross plates at the ends of said deck; means secured near the top edges of said cross plates for supporting said deck house plates; means secured near the longitudinal center of said cross plates for supporting the ends of said deck; and means secured near the bottom edge of said cross plates for securing them to the said barge frame.
16. In a barge construction, a frame, a wooden deck, deck house plates, log rails, gunwale plates extending over said log rails and secured thereto, vertical cross plates at the ends of the deck and extending upwardly as far as the gunwale plates, means at the upper edge of said cross plates for supporting the inner ends of the deck house plates, means at the longitudinal center of said cross plates for supporting the ends of the deck and means at the lower edge of said cross plates for securing said plates to the said barge frame.
- Signed at New York in the county of New York and State of New York this 29th day of August, A. D. 1929.
